No. 37,199.

Patented November 1, 1904.

UNITED STATES PATENT OFFICE.

WILLIAM F. SIMON, OF WEST HOBOKEN, NEW JERSEY.

DESIGN FOR A CHRISTMAS-TREE ORNAMENT.

SPECIFICATION forming part of Design No. 37,199, dated November 1, 1904.

Application filed October 6, 1904. Serial No. 227,487. Term of patent 7 years.

To all whom it may concern:

Be it known that I, WILLIAM F. SIMON, a citizen of the United States, residing at West Hoboken, in the county of Hudson and State of New Jersey, have invented a new, original, and ornamental Design for a Christmas-Tree Ornament, of which the following is a specification, reference being had to the accompanying drawings, forming a part thereof, and in which—

What I claim is—

The ornamental design for a Christmas-tree ornament, substantially as shown.

WILLIAM F. SIMON.
